MACHINE FOR TAPING SHOE PARTS

Fred L. Corson, Rochester, N. H., assignor to
 United Shoe Machinery Corporation, Paterson,
 N. J., a corporation of New Jersey

Application June 11, 1937, Serial No. 147,611

8 Claims. (Cl. 12—51)

This invention relates to machines for taping shoe parts and is herein illustrated as embodied in a machine organized to cut off from a strip of indeterminate length a measured piece of adhesive strengthening tape and apply it in predetermined position to the marginal portion of a shoe part, spaced inwardly from the edge thereof.

An object of the invention is to provide a shoe part taping machine which shall operate more rapidly and accurately than machines heretofore used for this purpose while requiring the exercise of no particular skill by the operator, thus reducing materially the cost of the taping operation and producing work of improved quality.

15 A feature of the invention consists in the combination with tape feeding mechanism and an elongated presser member which operates to apply an entire length of tape to a shoe part at one time of means for guiding a projected length of tape accurately to applying position upon the shoe part prior to its application thereto by the presser. In the illustrated machine the guiding means is yieldingly mounted upon the presser member itself and acts to hold the work piece down flat upon a work supporting table while the tape is being applied thereto.

Another feature resides in a combination of work piece positioning guides and tape severing tools so related to each other that the severed end of a piece of tape after it has been applied to a work piece terminates a predetermined distance within the adjacent boundary of the work piece, thereby eliminating any necessity for an operator to trim the end of the tape even with or short of the edge of the work.

35 These and other features of the invention, and advantages to be derived from its use, will be better understood and appreciated from reading the following detailed description of a practical embodiment thereof in connection with the accompanying drawings, in which

Fig. 1 is an angular view of the machine as seen from the front;

Fig. 2 shows a work piece with reenforcing tapes as applied by the machine;

Fig. 3 is an angular view of the machine as seen from the rear;

Figs. 4 and 5 are, respectively, side elevation and end views of a tape-guiding and holding device through which the tape passes as it comes off the tape-supplying roll;

Fig. 6 is a view partly in end elevation and partly in section of the work holder and tape-applying presser;

55 Fig. 7 is a view similar to Fig. 6 showing the

mechanism for holding the tape stationary and cutting it off;

Fig. 8 is a view illustrating details of the tape-holding and cutting mechanism;

Fig. 9 is a sectional view on the line IX—IX of Fig. 8;

Fig. 10 is a view illustrating details of the tape-feeding mechanism; and

Fig. 11 is a sectional view on the line XI—XI of Fig. 10.

All of the operating mechanism of the machine is mounted in or upon a base or frame 20 which is adapted to be bolted down on a bench. The movements of the various operating parts are all derived from a main shaft 22 which is journaled in bearings 24, 26 mounted upon the frame, power from a driven pulley 28 being supplied to the shaft through a one-revolution clutch 30 controlled by a treadle rod 32.

Journalized in a bearing 34 in the machine frame is a transverse shaft 36 to the rear end of which is fixed a gear 38 meshing with a similar gear 40 fixed to the main shaft 22. Secured to the front end of the shaft 36 is a crank disk 42 having a crank pin 44 connected by a connecting rod 46 to a slidable block 48 which is arranged for up and down adjustment in an arcuate slot 50 formed in a swinging arm 52. The arm 52 is movable about a pivot 54 which is mounted in the frame 20 and the said arm has bolted to it a bracket 56 which provides bearings for a rotatable screw 58 to the lower end of which is fixed a pinion 60. The pinion 60 meshes with a gear 62 fixed to a shaft 64 which is journaled in a bearing 66 in the arm 52 and has secured to its front end a hand crank 68.

The screw 58 is threaded through a nut 70 which constitutes a part of the sliding block 48 and upward or downward adjustment of the said block relatively to the arm 52 may be effected by rotating the screw by means of the hand crank 68. It will be understood that rotation of the crank disk 42 will cause the arm 52 to be swung back and forth through an angle, the magnitude of which is determined by the distance of the block 48 from the fulcrum 64.

To the upper end of the swinging arm 52 is pivoted at 72 a link 74 the other end of which is pivotally connected at 76 to a feed slide 78 guided for movement along stationary ways 80.

The feed slide includes a block 82 movable between the ways 80 and extending down to the lower edge thereof. Pivotally mounted on the slide at 84, beneath the block 82, is an upwardly extending toothed feed dog 86 which is so re-

lated to the block 82 that the tape 88 will be seized between the forwardly directed teeth 90 upon the dog and the under side of the block when the feed slide is moved to the left as viewed in Figs. 1 and 11 to feed the tape forward a measured distance determined by the setting of the block 48 and the resulting length of travel of the upper end of the arm 52.

The tape is obtained from a tape-supply roll 92 which is carried by a stationary bracket 94 mounted upon the frame 20. From the roll the tape passes through a guide 96 which is best shown in Figs. 1, 4 and 5. The guide 96 is secured to the frame 20 by screws 98 and pivotally mounted beneath it at 100 is a tape-holding dog 102 having forwardly directed teeth which engage the under side of the tape and hold the tape against the guide 96. The pivot 100 is surrounded by a torsion spring 104 one end of which is anchored at 106 and the other end of which engages the dog 102 at 108, the spring being so wound that it tends to hold the dog up against the tape. The function of this device is to permit the tape to be drawn forward from the supply roll but to prevent it from being pulled back.

Secured to the sides of the guideways 80 are plates 110 having at their lower edges flanges 112 which are turned inward beneath the ways 80, as shown in Figs. 9 and 10, the flanges being spaced a short distance below the lower edges of the ways to provide a space which constitutes a guideway for the tape. Across the left-hand end of the member 80 is arranged a bar 114 having through it a slot 116 through which the tape may emerge. Just before reaching the slot 116, the tape passes over a supporting roll 118 which assures that the tape will be guided accurately to the slot.

After emerging from the slot 116, the tape passes over a stationary blade 120 which cooperates with a movable blade 122 to form a shear couple by which the tape is cut off, as will be described hereinafter.

Mounted upon a bracket portion 124 of the frame 20 is a work-supporting table 126 upon which a work piece such as the shoe part 128, illustrated in Fig. 2, may be positioned and held while the tape is fed out upon it and applied to it by pressure. A back gage 130 for determining the position of the rear edge of the work piece is adjustably secured to the table 126 by screws 132 which pass through slots 134 in brackets 136 secured to the gage.

A side gage 138 against which the edge of the work piece may be positioned in the direction of the tape feed extends upward from an angular member 140 which is detachably secured to the work table 126 by a thumb screw 142 (see Figs. 2 and 6).

After being projected out over a work piece positioned upon the table 126 and cut off, the entire piece of tape, the adhesive side of which faces downward, is applied to the work piece at one time by an elongated presser 144 which is secured by screws 146 to a presser arm 148 movable about a horizontal pivot 150 supported in brackets 152 arising from the rear corner of the work table supporting bracket 124.

Also movable about the pivot 150 is an arm 154 between the forward end of which and the arm 148 is interposed a compression spring 156. Pivotally connected to the arm 154 at 158 is a link 160 the lower end of which is connected at 162 to a cam lever 164. The front end of the cam lever 164 is pivotally mounted at 166 in the machine frame and upon its rear end portion is formed a flat sur-

face 168 adapted for engagement with a cam 170 secured to the main shaft 22. A pull spring 172, attached at its upper end to the bracket 152 and at its lower end to the cam lever 164, holds the lever in engagement with the cam at all times and when the cam is rotated from the position shown in Fig. 3 to that shown in Fig. 6 it is apparent that the presser 144 will descend and press the tape into contact with the work piece, with pressure which is yielding by reason of the interposition of the spring 156 between the arms 148 and 154.

In order so to guide the tape after it has emerged from the slot 116 and is being projected out over the work piece that it will be accurately deposited upon the work piece a predetermined distance within the adjacent boundary thereof, and also in order to clamp and hold the work piece flat upon the table 126 while the tape is moving out over it, plates 174 are provided, one on each side of the presser 144. The plates 174 are secured to saddles 176 which are vertically movable upon pins 178 fixed in the presser 144. These pins are surrounded by compression springs 180 which normally hold the plates 174 down, thus providing a guide channel for the tape, but yield to permit the presser 144 to continue to descend after the lower edges of the said plates engage the work piece 128. By thus engaging and bearing upon the work piece the plates 174 clamp and hold the latter down upon the work table 126.

In order to cut off the projected tape before it is applied to the work piece by the presser 144, provision is made for actuating the upper shear member 122 at the proper time. The shear member 122 is secured to a lever 182 which is movable about a stationary pivot 184 and has its rear end connected by a link 186 to a cam lever 188 having a flat surface 190 arranged to be engaged by a cam 192 secured to the main shaft 22. The forward end of the cam lever 188 is movable about the pivot 166 and the lever is drawn downward into engagement with the cam 192 by a pull spring 194 the lower end of which is anchored at 196 to a bracket 198 bolted to the machine frame.

Between the link 186 and the pivot 184 the shear lever 182 is connected by a link 200 to the rear end of a lever 202 movable about a stationary pivot 204 and having secured in its forward end a pointed pin 206 adapted to penetrate the tape and hold the latter positively against movement in either direction while it is being cut off and the feed slide is being retracted for the feed dog 86 to obtain a fresh grip upon the tape ready for the next feeding operation.

The lower portion of the bar 114 is recessed as shown at 208 (Figs. 1 and 8) so that when the edge of the work piece 128 is positioned against the wall of the recess the work piece will be so located with reference to the shear member 122 that the severed end of the cut-off piece 210 of tape when it is applied to the work piece will terminate within the edge of the latter, thereby eliminating any necessity for an operator to trim the end of the tape even with, or short of, the edge of the work.

The timing of the various mechanisms is such that the tape is first projected out between the guide plates 174 upon the work piece, next penetrated by the pin 206 and held while it is cut off, and then pressed firmly into adhesive contact with the work piece by the presser 144. Finally the machine stops with all of the operating instrumentalities retracted to permit removal of 75

the work piece to which the tape has been applied.

Having described the invention, what is claimed as new and desired to be secured by Letters Patent is:

5. In a machine for taping shoe parts, the combination of mechanism for projecting a measured length of tape over a shoe part, pressing means for applying the entire length of the tape to the 10 shoe part at one time, and means for guiding the length of tape continuously by its edges as it is projected to applying position and prior to the operation of the pressing means.

15. In a tape applying machine, the combination of a work support, a tape applying presser mounted for vertical movement above the work support, yieldingly mounted work clamping members extending uninterruptedly along the sides of the presser, and means for projecting a tape between the clamping members, said members constituting means for continuously guiding the tape 20 to applying position beneath the presser.

25. In a tape applying machine, the combination of a work support, an elongated tape applying presser mounted for movement toward the work support, a pair of elongated work clamping plates, each extending uninterruptedly along its respective side of the presser, said plates and presser being arranged to form a continuous tape 30 guiding channel, and means for projecting a measured length of tape into said channel beneath the presser.

35. In a tape applying machine, the combination of a support for a shoe part, means for projecting a measured length of tape upon a shoe part on the support, continuous means extending along both edges of the length of tape for so guiding it while it is being projected that it will be accurately deposited in applying position, a 40 tape applying presser, means for operating the presser, and means for severing the length of tape after it is projected and before the presser operates upon it.

5. In a tape applying machine, the combination of a work support, gaging means for positioning a shoe part accurately upon the support, tape applying mechanism, means for projecting a measured length of tape upon the positioned 5 shoe part, and tape severing means so related to said gaging means that the length of tape severed thereby will terminate a predetermined distance within the adjacent boundary of the shoe part.

10. In a tape applying machine, the combination of a work support, gaging means for positioning a shoe part accurately upon the support, tape applying mechanism, and means for projecting and guiding a measured length of tape upon the positioned shoe part, said tape projecting and guiding means and said gaging means being so related that the length of tape will be deposited upon the shoe part a predetermined 15 distance within the adjacent boundary thereof.

15. In a tape applying machine, a tape applying 20 presser, means for yieldingly operating the presser, and a tape guide extending uninterruptedly lengthwise on both sides of the presser and mounted yieldingly thereon.

25. In a tape applying machine, a combination 25 tape applying presser, tape guide, and work clamp, comprising a presser which is at least as long and as wide as the length of tape to be applied, a pair of uninterrupted plates, each extending along its respective side of the presser 30 for substantially the full length of the presser, the edge portions of said plates normally projecting past the tape engaging face of the presser to form therewith a complete tape guiding channel, saddles joining said plates together, and 35 yielding spring connections between said saddles and the presser, whereby the plates are carried by the presser and can yield relatively thereto when the edges of the plates engage a work piece prior to pressing engagement of the presser with the 40 tape.

FRED L. CORSON.
